CLAIM

The ornamental design for a RV waste tank cleaning tool, as shown and described.

DESCRIPTION

FIG. 1 is a perspective view showing the RV waste tank cleaning tool showing my new design;

FIG. 2 is an enlarged, fragmented front elevational view thereof, with the handle shown broken away for ease of illustration only;

FIG. 3 is a left side elevational view thereof, the opposite side being a mirror image;

FIG. 4 is a rear elevational view thereof;

FIG. 5 is a top plan view thereof; and,

FIG. 6 is a bottom plan view thereof.
